DESIGN FOR A DECANTER TYPE BOTTLE

James V. Mondi, Chicago, Ill.

Application February 26, 1935, Serial No. 55,625

Term of patent 3½ years

To all whom it may concern:

Be it known that I, James V. Mondi, citizen of the United States, and residing at Chicago, county of Cook, and State of Illinois, have invented a new, original, and ornamental Design for a Decanter Type Bottle, of which the following is a specification, reference being had to the accompanying drawing, forming a part thereof.

of the neck of my decanter type bottle, showing my new design, on the plane 3—3 of Figure 2.

I claim:

The ornamental design for a decanter type bottle as shown.

In witness whereof I affix my signature.

JAMES V. MONDI.
